UNITED STATES PATENT OFFICE.

FRANK H. LA PIERRE, OF EAST ORANGE, NEW JERSEY.

DESIGN FOR A BRUSH-BACK OR SIMILAR ARTICLE.

SPECIFICATION forming part of Design No. 30,044, dated January 24, 1899.

Application filed December 22, 1898. Serial No. 700,065. Term of patent 7 years.

To all whom it may concern:

Be it known that I, FRANK H. LA PIERRE, a citizen of the United States, residing at East Orange, in the county of Essex and State 5 of New Jersey, have invented and produced a new and original Design for Brush-Backs or Similar Articles; and I do hereby declare the following to be a full, clear, and exact description of the invention, such as will 10 enable others skilled in the art to which it appertains to make and use the same, reference being had to the accompanying drawings, and to letters of reference marked thereon, which form a part of this specification.

15 Figure 1 is a plan view of a hair-brush having a back of my new design; and Fig. 2 is a sectional view of the same on line α , Fig. 1.

As shown in the drawings, the leading or 20 material feature of my newly-designed brush-back consists in a large polka-dot ornament placed at the center of the larger portion of a brush-back ornamented by small dots distributed over a plain ground.

In said drawings, a indicates the larger or 25 body portion of the brush, said body portion

being in plan ovally rounded at the end and having its convex side outlines converging toward the handle b of the brush. Concave curves c outline that portion of the handle adjacent to the body portion of the brush, 30 and rearwardly beyond said concave curves the handle is approximately oval in general outline. The edges of the brush-back are rounded off, as at d , and the plain surface of the back is ornamented with small dots e . 35

The back of the larger portion a of the brush is ornamented by a polka-dot i , centrally disposed upon the dotted ground and being of much larger size than the dots in said ground. 40

What I claim as new is—

The design for a brush-back or similar article, as herein shown and described.

In testimony that I claim the foregoing I have hereunto set my hand this 24th day of 45 September, 1898.

FRANK H. LA PIERRE.
